CLAIM

The ornamental design for a floating spa cover, as shown and described.

DESCRIPTION

FIG. 1 is a top, front perspective view of a floating spa cover showing our new design; the bottom perspective view being a mirror image;

FIG. 2 is a rear elevation view thereof; the left and right side elevation views being identical;

FIG. 3 is a front elevation view thereof;

FIG. 4 is a top, front perspective view of a second embodiment showing our new design; the bottom perspective view being a mirror image;

FIG. 5 is a rear elevation view thereof; the left and right side elevation views being identical;

FIG. 6 is a front elevation view thereof;

FIG. 7 is a top, front perspective view of a third embodiment showing our new design; the bottom perspective view being a mirror image;

FIG. 8 is a rear elevation view thereof; the left and right side elevation views being identical; and,

FIG. 9 is a front elevation view thereof.
